(57) **CLAIM**

The ornamental design for a reconfigurable zippered sea otter sleeping bag, as shown and described.

DESCRIPTION

FIG. 1 is a perspective view of the reconfigurable zippered sea otter sleeping bag showing my new design;

FIG. 2 is the front view thereof;

FIG. 3 is the back view thereof;

FIG. 4 is the reduced scale side view thereof;

FIG. 5 is a front view thereof, in a transitional position with the neck and body zippers partially opened;

FIG. 6 is a front view thereof, in an alternate completely open position of use; and,

FIG. 7 is a front view thereof, shown in use with a child sleeping within.

In the drawings, the broken lines representing the zippers and a child form no part of the claimed design.
